Corporation, Oakmont, Pa., a corporation of
Pennsylvania

Application December 14, 1938, Serial No. 245,634

8 Claims. (Cl. 80—60)

This invention pertains to the forming of an annuli having an internally projecting flange by rolling. According to this invention there is provided a novel method of forming such object and an improved apparatus through which the method may be effected. The present application is directed to the novel method, while the apparatus is the subject of divisional application Serial Number 404,032 filed July 25, 1941.

Internally flanged annuli are commonly made at the present time by die forging. Some success has heretofore been achieved in producing such articles on ring rolling mills, but this is difficult because of the peculiar conditions which are encountered in expanding a pierced blank or bloom from its original form to an internally flanged ring of many times the diameter of the blank. Among other difficulties encountered is the fact that the metal in the different portions of the blank is elongated at different rates. For example, if an annulus is being rolled which is T shaped in cross section with the stem of the T extending radially inwardly to form the internal flange and the part corresponding to the cross-bar of the T extending in an axial direction, the parts of the metal forming the rim above and below the plane of the leg or flange portion are elongated at a rate considerably out of proportion to the rate at which the cross section of metal in the plane forming the flange is elongated. The same is true in the rolling of a blank of L shaped cross section where the base of the L turns inwardly, such a blank or a modified form of it being commonly used for ring gears.

According to our invention internally flanged annuli are formed from a pierced bloom by a rolling operation effected in a ring mill and the operation is carried out in such a way that the rate of elongation for different parts of the section can be controlled and coordinated to the elongation in other parts of the section. According to the present invention it is further contemplated that the rolling of the rim portion of the annulus and the rolling of the flanged portion may take place concomitantly in different steps, each of which steps can be correlated or varied with respect to the other whereby the elongation of any particular part of the section can be regulated or adjusted with respect to the elongation of the other parts of the section either to have reduction in all parts of the section take place at the same rate or at controlled different rates.

Our invention may be understood by reference to the accompanying drawings in which—

Figure 1 is a more or less schematic view showing a side elevation of the roller arrangement of a ring mill for practicing our invention with a partially rolled blank engaged in the rollers;

5 Figure 2 is a top elevation of the arrangement shown in Figure 1, the wheel and guide rolls being more clearly shown than in Figure 1;

Figure 3 is a view showing a typical blank or bloom in the form in which it is originally made up for reduction in the mill;

10 Figure 4 is a similar view of the completed blank;

Figure 5 is a longitudinal section showing more or less schematically a ring mill of novel construction arranged for carrying out the method of our invention; and

Figure 6 is a detailed view showing an elevation of the arbor and support for the upper edging roll of the ring mill shown in Fig. 5.

20 Referring more particularly to the drawings, Fig. 4 shows one typical form of internally flanged annulus which is formed by the present invention. The internally extending flange in the particular example illustrated is in the middle plane

25 of the rim, the section through the rim being generally of a T shape with the leg of the T extending inwardly, but in many cases the flange may be above or below a middle plane or the section may be an L or a Z shape, or have some other form. In forming the flanged annulus of Figure 4, a blank or bloom such as that shown in Figure 3 is first prepared. The blank may be formed in the usual way by forging a section of a billet to produce an annular bloom.

35 The apparatus employed comprises a power driven main roller 2 adapted to bear against the periphery of the bloom or blank. Cooperating directly with the main roller 2 is a pressure roller 3 (see Figs. 1 and 2). The pressure roller 3 is supported for movement in a direction toward or away from the main roll 2. The rolling pass provided between the main roll 2 and the pressure roll 3 determines the reduction of the dimension F of Fig. 3 to the dimension F' of Fig. 4. The 40 rolling of the blank between these rolls effects reduction primarily in the plane of the flange of the blank. Acting in conjunction with the rolls 2 and 3 are upper and lower edging rolls 4 and 5 respectively. These rolls 4 and 5 are inclined toward each other and they are in the same vertical plane and they are diametrically opposite rolls 2 and 3. For rolling the particular shape illustrated, the upper edging roll 4 has a shouldered work-engaging portion 4', and the lower 45 edging roller 5 has a similar shouldered working

portion 5'. Roll 4 contacts with surfaces a, b, and c of the blank or bloom. The working portion of the roll 5 contacts the surfaces a', b', and c' of the blank shown in Figure 3. They are both supported on a carriage so that they can be moved toward and away from the main roll 2. In the operation of rolling they are moved away from the main roll 2 as the diameter of the annulus increases. Equidistantly spaced to each side of the edging rollers 4 and 5 are pressure rollers 6 and 7 which we designate as wheel rolls and which bear against the periphery of the blank. The wheel rolls are mounted on the same carriage as the edging rolls 4 and 5, as will be hereinafter more fully explained, so that they may be moved away from the main roll 2. They are also mounted for relative movement with respect to the edging rollers 4 and 5 so that they can move in the direction of the arrows in Fig. 2; i. e., toward the left as viewed in Fig. 2 at the same time as the carriage which carries both the edging rolls and the wheel rolls as viewed in Fig. 2 is moving toward the right. It is through the manipulation of the wheel rolls 6 and 7 toward the shouldered terminals of the edging rolls 4 and 5 that the change of dimension A in Fig. 3 to A' in Fig. 4 is effected. The combination of edging and wheel rolls effects reduction in a radial direction in that portion of the blank above or below the plane of the flange.

In addition to this, the upper edging roll 4 is movable vertically toward and away from the lower edging roll. It is through this relative vertical movement that the dimension B of Fig. 3 is changed to B' in Fig. 4, and dimension C in Fig. 3 is reduced to C' in Fig. 4, dimension C' being the thickness of the flange. The dimensions of the rolls 4 and 5 determine the changing of dimensions D and E of Fig. 3 to D' and E' of Fig. 4. Through the joint manipulation and action of all of the rolls, the over-all dimension X of the blank of Fig. 3 is increased to X' in Fig. 4 and the internal diameter, dimension Y in Fig. 3, is increased to Y' in Fig. 4.

In addition to the various rolls mentioned, the ring mill also has guide rolls 8 and 9 equidistantly spaced from the main roll 2 which bear against the periphery of the blank, the function of which is to keep the blank in a truly circular shape as it is rolled. The guide rolls 8 and 9 are supported for movement in an arc as indicated by the arrows in Figure 2.

In rolling an internally flanged annulus according to the present invention utilizing the combination of rolls described, the blank after being forged into the shape shown in Fig. 3 and while still hot, is engaged by rolls in such manner that the pressure roll 3 extends through the opening in the blank while the main roll 2 bears against the periphery of the blank. At this time the rollers 4 and 5 instead of being shown as shown in Fig. 1 are separated to a considerably greater extent than in Fig. 1 and they are much closer to the pressure roll 3. They are adjusted so that the roll surface of the blank rests on the terminal portion 5' of the lower edging roll 5 and the terminal portion 4' of the upper edging roll is brought down to engage the blank so as to engage surfaces a, b, and c. When the blank has been thus positioned in the rolls, the wheel rolls 6 and 7 are brought into engagement with the periphery of the blank. In addition to the main roll 2 being power driven, the edging rolls 4 and 5 are also power driven.

When a blank has been positioned between

the rolls in the manner described, the driven rolls 2, 4, and 5 are put into operation causing the blank to be rotated. When a suitable rolling speed has been reached, the roll 3 is moved toward the roll 2. At the same time the roll 4 may be gradually or intermittently let down with reference to the lower edging roll 5. During the rolling operation the edging rolls 4 and 5 are moved gradually in a direction away from the main roll 2. The wheel rolls 6 and 7 are moved with the edging rolls 4 and 5 away from the main roll 2 and at other times they may be moved gradually or in small increments toward the terminals 4' and 5' even while the assembly comprising the edging rolls 4 and 5 and the wheel rolls 6 and 7 as a whole is moved toward the right as viewed in Figs. 1 and 2. The movement of the pressure roll 3 toward the main roll 2 determines the ultimate dimension F' as indicated in Fig. 4. The relative movement between the wheel rolls 6 and 7 and the edging rolls 4 and 5 causes the edging rolls to establish the width of the rim portion of the annulus; i. e., the dimension A' of Fig. 4. Thus, while the dimension of the blank in the plane of the flange is being determined by the rolls 2 and 3, the thickness of the rim, A' as viewed in Fig. 4, is being established through the pressure exerted by the edging rollers applying a rolling pressure against the surfaces c and c' in Fig. 3 of the blank while the wheel rolls 6 and 7 are bearing against the periphery of the blank. In some rolling operations the wheel rolls 6 and 7 may remain fixed relative to the edging rolls 4 and 5, but the metal may nevertheless be reduced in a radial direction between the shoulders of the edging rolls and the wheel rolls, because as the piece becomes larger in diameter, either from the relative movement of the edging rolls towards each other or from the movement of the pressure roll 3 towards the main roll 2, the periphery of the annulus being rolled is forced closer to the shoulder portion of the edger rolls, which causes a reduction to take place in a radial direction in that portion of the annulus which is outside the plane of the internal flange. The main roll 2 and the pressure roll 3 are thus operating to reduce the metal in the plane of the flange at the same time that the edging rollers, in conjunction with the wheel rolls, are reducing the portion of the blank that forms the rim of the annulus, but the rate of reduction of these portions can be independently controlled. Reduction in the cross section of the blank as a whole is further secured through the vertical movement of the upper edging roll with respect to the lower edging roll 5. As the upper edging roll 4 is forced down, pressure is applied in the direction of the axis of the blank against the faces a and a' of the rim and faces b and b' of the flange.

It will therefore be seen that three generally independent operations are correlated in the forming of a flanged annulus in accordance with our invention. Elongation takes place when the pressure roll 3 is moved toward the main roll 2. Elongation takes place when the wheel rolls 6 and 7 are moved toward the shouldered terminals of the edging rolls, and elongation takes place when one of the edging rolls is moved vertically toward the other. Through the use of properly constructed edging rolls having working surfaces capable of applying both a downward and a radial pressure, the rate of reduction of the rim portion of a flanged annulus can be correlated

to the rate of reduction of the portion of the blank in the plane of the flange. In the rolling of the shape shown in Fig. 4 from the blank shown in Fig. 3, dimension F of Fig. 3 may be reduced, say one inch, to dimension F' in Fig. 4, and dimension A may be reduced one inch to dimension A' of Fig. 4. While this is the same actual reduction, one inch represents a considerably greater percentage of reduction on the dimension A than it does on the dimension F. From this example the importance of being able to correlate the reduction of the metal in the zone of the flange to the reduction of the metal in the remaining part of the rim becomes more apparent. Likewise, dimension X is expanded to dimension X' at a slower or different rate than dimension Y is expanded to dimension Y', and the present invention enables the blank to be expanded notwithstanding these different rates at which the diameter in different portions increases without drawing or stretching the metal. It will be noted, moreover, that the faces b and b' and the inner face of the flange are all formed by a true rolling action so as to develop the grain of the metal.

One form of apparatus which may be used to a limited extent for practicing our invention is fully illustrated and described in U. S. Patent No. 1,350,057 to F. B. Bell dated August 17, 1920, which shows a ring rolling mill of the type herein referred to having a power driven main roll and a pressure roll, corresponding to rolls 2 and 3 respectively, and having upper and lower edging rolls corresponding generally to rolls 4 and 5, the upper edging roll being adjustable. This patent also shows wheel rolls supported for movement toward and away from the terminals of the edging rolls, the wheel rolls and edging rolls being all supported on a carriage which can be moved away from the main roll as the diameter of the ring increases. In the said prior Patent No. 1,350,057 the edging rolls are used to control the thickness of the annulus in the direction of the axis of the annulus. The upper edging roll moves up and down with respect to the lower one only in an arc.

Because the apparatus shown in the Bell patent was not designed for use in rolling flanged annuli, and because the upper edging roll can move with respect to the lower one only in an arc, its use in carrying out our method is limited, and we therefore prefer to, and as a matter of practice do, secure more satisfactory results and can roll a wider range of shapes, by using a machine as illustrated in Figs. 5 and 6 where the upper edging roll may be moved toward and away from the lower edging roll in a direction parallel with the axis of the annulus being rolled instead of in an arc, as in said Frank B. Bell patent. Referring to Figs. 5 and 6, 10 represents a stationary frame member providing bearings for a shaft 11 on which is mounted the main work roll 2, the shaft being driven by a motor 12. 13 designates a horizontal bed. Set on the bed 13 is a slide 14 providing a support for the pressure roll 3. Connected to the slide 14 is a pull rod 15 which is illustrated as having a cross head 16 on which are pistons engaging in cylinders 16', such cylinders being mounted on the stationary frame 10. The arrangement is such that when the cylinders 16 are operated, the slide 14 may be moved back and forth for moving the pressure roll 3 toward the main roll 2. Also mounted on the bed 13 is a carriage 17. This carriage has a vertically extending arbor 18 at its forward end. Mounted

in the arbor 18 is a cross head 19 having a piston 20. There is a vertically reciprocable carriage 21 mounted in the arbor, the arbor providing a slideway for guiding the carriage 21 vertically. The carriage 21 is provided with a cylinder 22 cooperating with the piston 20. Pivotally suspended from the lower end of the carriage 21 is a bracket 23 on which is mounted a slide plate 24. On the slide plate 24 is a motor 25. The motor 25 drives a shaft 26 on the lower end of which is the upper edging roll 4. A screw adjustment 27 enables the motor with the shaft 26 to be moved in the direction of the axis of the shaft 26 to advance or retract the upper edging roller. A yoke 28 is attached to the bracket 23. It is also adjustably connected at 29 to a bracket 30 on the carriage 21. Through the operation of the adjustment 29 the angle of the shaft 26 and of the upper edging roll can be changed. 31 indicates a pull-back cylinder for raising the carriage, this cylinder being operable through pull-back rods 32. The carriage 17 also provides a support for the lower edging roll 5. This roll is carried on a shaft 5a. Any suitable drive arrangement may be provided for the shaft as for example the drive arrangement shown in the said patent to F. B. Bell or there may be a motor 33 on the carriage for driving the shaft 5a as illustrated in Fig. 5. There is also illustrated a screw adjustment 34 by means of which the motor shaft 5a can be moved up and down in the direction of the axis of the shaft 5a for adjustment of the roll 5 with respect to the roll 4.

Also mounted on the carriage 17 is a fixed cylinder 35 which operates a piston rod 36. On the forward end of the piston rod 36 is a yoke 37. This yoke supports the two wheel rolls 6 and 7. In conjunction with cylinder 35 there may be a pull-back cylinder 38. By operation of the piston 36, wheel rolls 6 and 7 can be moved back and forth with relation to the edging rolls 4 and 5.

The carriage 17 can be moved back and forth. For effecting the operation of the carriage, we have shown a cylinder 39 having a piston with a piston rod 40, the forward end of the piston rod 40 being connected to the carriage. The arrangement is such that by operation of the cylinder, the carriage 17 can be moved back and forth along the bed of the machine.

The mechanism illustrated is more or less schematically shown as being one type of structure specifically adapted for carrying out our invention. The important difference between the structure shown in Fig. 5 and prior Patent No. 1,350,057 is the arrangement whereby the upper edging roll 4 may be caused to travel up and down in the arbor 18 in a direction parallel with the axis of the main roll 2 and the pressure roll 3. A further difference resides in the fact that the upper edging roll, in addition to being movable up and down in a direction parallel with the axis of the main roll, may also be adjusted to a desired angular inclination and retained at this inclination throughout the rolling operation. This is of importance in the rolling of different specific internally flanged shapes, as the angle of the upper work roll can be adjusted to meet the requirements of the particular annulus being rolled. By having the upper edging roll move vertically relatively to the lower one, the reduction in the piece being rolled caused by the upper roll being moved down occurs uniformly, whereas, an apparatus as shown in the Bell patent, while satisfactory for some shapes, causes

unequal reduction to occur by reason of the angular travel of the upper edging roll.

It will be understood from the description of our method that in the operation of rolling a flanged annulus the blank as shown in Figure 3 is placed between the main roll 2 and the pressure roll 3 in such manner that the pressure roll 3 passes through the opening in the blank. At this time the carriage 17 is in a position where the bottom face of the blank will rest on and be supported by the lower work roll 5. As the reduction of metal takes place causing the diameter of the blank to increase, the carriage 17 is moved to the right as viewed in Fig. 5 away from the main roll. As previously explained, reduction of the rim of the blank is accomplished by causing the wheel rolls 6 and 7 to move toward the edging rolls as viewed in Fig. 5 even though the carriage 17 as a whole may be receding from the main roll 2. Reduction of the rim portion as well as of the flange is also accomplished by the vertical movement of the upper edging roll toward the lower edging roll through the operation of the cylinder 22 and the piston 20. Reduction of the section of the metal lying in the plane of the flange of the annulus is effected through the movement of the pressure roll 3 toward the main roll 2, this being accomplished by causing the carriage 14 to be moved to the left as viewed in Fig. 5.

Various changes may be made in the apparatus illustrated, and various modifications may be made in the arrangement of rolls or combinations of rolls, depending upon the shape of the internally flanged annulus to be produced. Also, the order in which various combinations of rolls are operated may be varied to accomplish the best results for a given shape of annulus. For example, in the making of some annuli it may be desirable to effect elongation by moving the upper edging roll 4 down toward the lower edging roll 5 the full distance of its downward travel before moving the wheel rolls 6 and 7 inwardly toward the edging rolls. In other operations it may be desirable to just reverse this procedure while in still other operations the relative movement of the rolls may be effected in the increments alternating first between one set of rolls and then the other, or relative movement may be effected simultaneously. Also, instead of the annulus being of a T shape, as described, it may be in the form of an L or a Z, or any other cross sectional shape, and the edging rolls and other rolls are modified according to the shape to be rolled.

We claim as our invention:

1. The method of rolling an internally flanged annulus which comprises forming an annular bloom and then subjecting it to rolling operations in radial and axial directions, the portion of the blank in the plane of the flange being subjected to a radial rolling step separate from but in conjunction with the rolling in a radial direction of the remainder of the rim.

2. The method of rolling an internally flanged annulus which comprises forming an annular blank and then rolling the blank to reduce its section and increase its diameter, the portion of the blank in the plane of the flange and the remaining part of the blank being separately but concomitantly subjected to rolling pressure in a direction radially of the blank.

3. The method of rolling an internally flanged annulus which comprises forming an annular blank and then rolling the blank to reduce its section and increase its diameter, the portion of the blank in the plane of the flange and the remaining part of the blank being separately but concomitantly subjected to rolling pressure in a direction radially of the blank and at separately controlled rates.

4. The method of rolling an internally flanged annulus which comprises forming a blank in the form of an annulus and then rolling the blank to reduce its cross section and expand its diameter by separate radial rolling operations concomitantly performed on the rim portion of the annulus and on the flange portion, and simultaneously applying rolling pressure in an axial direction to both the rim and flange portions of the blank.

5. The method of rolling an internally flanged annulus which comprises forming an annular bloom and then subjecting it to rolling operations in radial and axial directions, the portion of the blank forming the rim of the annulus being subjected to a rolling operation in a radial direction separate from and in addition to a radial rolling step concomitantly performed on the blank against the flange portion thereof.

6. The method of rolling an internally flanged annulus which comprises forming an annular bloom and then subjecting the bloom to a rolling operation wherein the portion of the bloom in the plane of the flange is rolled between rollers which exert pressure in a radial direction and wherein the portions of the rim of the annulus which are offset from the plane of the flange are concomitantly rolled between rollers that exert pressure in a radial direction to said offset rim portions only.

7. The method of rolling an internally flanged annulus which comprises forming an annular bloom and then subjecting the bloom to a rolling operation wherein the portion of the bloom in the plane of the flange is rolled between rollers which exert pressure in a radial direction and wherein the portions of the rim of the annulus which are offset from the plane of the flange are concomitantly rolled between rollers that exert pressure in a radial direction to said offset rim portions only, and which also apply rolling pressure to both the flange and the rim portion of the bloom in the direction of the axis of the bloom.

8. The method of rolling an internally flanged annulus which provides forming an annular bloom and rolling the bloom by the application of pressure in a radial direction to reduce the section of the bloom in the portion of the blank in which the flange is to be formed, separately and concomitantly applying pressure in a radial direction to the rim portion of the blank extending beyond the flange, simultaneously applying pressure in an axial direction to the faces of the rim and the flange portions of the blank, and correlating the various applications of pressure to maintain the percentage of reduction in the flange and rim portions substantially uniform.
